UNITED STATES PATENT OFFICE

HUBERT JEZLER, OF ZURICH, SWITZERLAND

STEAM BOILER

Application filed February 27, 1931, Serial No. 518,760, and in Switzerland March 5, 1930.

The present invention relates to a steam boiler in particular a high pressure boiler.

The main object of my invention is to improve the thermal efficiency of steam generating plants generally and to provide a boiler which generates steam most economically.

I attain these and other objects by a boiler comprising a primary part in which water is heated near to its boiling point, care being taken that no considerable evaporation takes place, and a secondary part in which evaporation of the highly preheated water takes place and in which the steam may be superheated.

According to the invention a throttle and regulating device is arranged between the primary and the secondary parts, and a regulating device for the boiler feed which, preferably at the same time, serves the purpose of a safety valve.

In the primary part, the pressure and temperature of the water is held within such limits that here no appreciable evaporation is possible; this part of the boiler, therefore, remains filled with water at a high temperature during the working. This water flows through a throttle device into the secondary part of the boiler where it is first transformed into steam, which is superheated afterwards.

In the attached drawing, an example of a boiler according to the invention is shown diagrammatically in axial section.

The boiler shown comprises a primary part 1 with the furnace and the secondary part 2, which two parts are connected with each other by pipes 13, 14 and 16 and a valve 3. The valve 3 comprises a casing 21 in which a piston 15 is slidably mounted. A coiled spring 22, pressing the valve body 23 on its seat, tends to close the communication between the parts 1 and 2. Combustion takes place principally in the combustion chamber 7, from which the heating gases are drawn through tubes 8 and flow consecutively through tubes of the evaporator 2 and to the preheater 6.

The feed water is supplied through a pipe 9 into the cylinder 25 of the device 4, governing the feeding. A piston 10 of the device

4 is provided with an annular groove 26 which, in the position shown in the drawing, opens the water inlet for the feed water pump 5. By means of the pump 5, the water is forced through the pipe 11 to the preheater 6. The rate of flow of the feed water in the preheater 6 is kept low. The heated water leaves the preheater 6 through the pipe 12, and passes into the primary boiler 1. After it has passed over the heating surfaces of this, and has been further heated, it flows through the connecting pipes 13, 14. The valve 3 is kept closed by spring 22 acting on valve spindle 15. On the opening of the throttle valve 3, the highly heated water flows through the pipe 14 into the evaporator and superheater 2. The superheated steam formed in part 2, finally reaches the engine through the pipe 17, part of the steam flows through the branch 18 to the feed water pump 5.

The feed water regulation takes place as follows:

On the piston 10 of the device 4 acts a spring 27, said piston 10 is moreover influenced by the boiler pressure by means of the connecting pipe 19. If the boiler pressure rises piston 10 is forced upwards against the action of spring 27 until the feed water pipe 9 is closed. Should the boiler pressure rise still further, then the piston 10 is forced up higher, so that the outlet 20 is opened with an immediate fall of pressure in the boiler 6. When the piston 10 returns a reversal of the flow of fluid in the pipe 19 takes place, the feed water inlet is opened by the groove 26 in the piston 10, and the water passes again to the feed water pump 5 and from the pump 5 into the preheater 6.

In the present example, a continuously running feed pump 5 is provided, the water inlet of which is controlled by the device 4. A device 4 may, however, be used controlling the steam supply to the feed pump so that the pump works only during periods of supply.

The throttling device 3 is contrived as follows:

The inner diameter of the pipe or nozzle 14 is made so that in no case more water can

flow through than can be evaporated and superheated in the secondary part 2. By means of the valve body 15, 23 which is under spring pressure and which may be operated in any suitable manner, for example by a speed governor, the quantity of steam is exactly suited to the consumption. The pressure acting on valve spindle 15 is higher than the pressure acting on the piston 10 of the device 4, consequently an increase in steam pressure in the boiler to a predetermined extent, will move the piston 10, but not the valve spindle 15. It is understood that the throttling and regulating device 3 is only conventionally illustrated, and in practice may have various details or features employed in a modern speed governor.

The advantages of the boiler according to the invention, in particular of a high pressure boiler, as compared with others, are much as follows:—

A boiler which remains constantly filled with water requires little attention. The feeding of such a boiler is extremely simple, since it can be effected with certainty and entirely automatically by means of a suitable device. The regulating device can also serve as an overflow, in which case a separate safety valve is unnecessary. As the position of the pistons used in the regulating device corresponds to the working condition at the moment, the use of level indicators or water gauges is not necessary.

In the primary part no steam is generated or only a very small production of steam takes place, and the boiler water is only subjected to heating and to a slight circulation and not to ebullition.

A further advantage of the boiler according to the invention is that in working it for example with coal dust or oil firing, the construction of expensive boiler drums is not necessary.

What I wish to claim and secure by U. S. Letters Patent, is:—

1. In a steam generating plant, a feed water preheater, a pump for delivering feed water thereto, a valve for controlling the intake to said pump, a chamber connected to said preheater, and a piston in said chamber and operated by the pressure of the water in said chamber and operatively connected to said valve to close the latter when said pressure exceeds a predetermined limit, said chamber having an outlet controlled by said piston to permit escape of water from said preheater when the pressure exceeds a predetermined limit.

2. In a steam generating plant, a water heater, a valve casing, a reciprocating mem-

ber in said casing, a connection between said chamber and said water heater for permitting delivery of water from said heater to said chamber to force said member in one direction, a pump for delivering water to said heater, and water supply connections between said casing and the inlet of said pump, said connections being closed by said member when the pressure in said heater exceeds a predetermined limit, and said casing having an outlet also controlled by said member for permitting escape of liquid from said heater when the pressure in the latter exceeds a predetermined limit.

3. In a steam generating plant, a water heater, a pump for delivering water thereto, a valve for controlling the intake to said pump, a piston for operating said valve to close the latter when the pressure in said heater exceeds a predetermined limit, a cylinder inclosing said piston, connections between said piston and said water heater, and an outlet permitting escape of water from said water heater, said outlet being controlled by said piston.

4. In a steam generating plant, the combination of a heating unit for water, a feed pump for delivering water to said unit, and valve mechanism automatically operated in accordance with the pressure of the water in said unit and having means for controlling the flow of water to said pump, and means for relieving the pressure in said unit when the pressure therein exceeds a predetermined limit.

5. In a steam generating plant, the combination of a water heating unit, a feed pump for delivering water to said unit, and a control member operating in accordance with the pressure in said unit for controlling the flow of feed water into said unit and for permitting or preventing bleeding of water from said unit.

6. A steam generating plant including a primary chamber for storing water under a pressure below the critical pressure, a secondary chamber for storing water under a lower pressure and constituting a combined evaporator and superheater, a feed pump for delivering water to said primary chamber to maintain the latter completely filled with water, an outlet from the top of said primary chamber to said secondary chamber and having a throttle valve, and a spring tending to close said valve against the pressure in said primary chamber, said valve being mechanically operable to permit delivery of water to said secondary chamber at a rate depending upon the steam consumption.
